UNITED STATES PATENT OFFICE.

SEYMOUR H. ROSENBERG, OF NEW HAVEN, CONNECTICUT, ASSIGNOR TO
I. ROSENBERG & CO., OF SAME PLACE.

DESIGN FOR A CORSET.

SPECIFICATION forming part of Design No. 13,284, dated September 5, 1882.

Application filed August 10, 1882. Term of patent 3½ years.

To all whom it may concern:

Be it known that I, SEYMOUR H. ROSENBERG, of New Haven, in the county of New Haven and State of Connecticut, have invented a new Design for Corsets; and I do hereby declare the following, when taken in connection with accompanying drawing and the letters of reference marked thereon, to be a full, clear, and exact description of the same, and which said drawing constitutes part of this specification, and represents a side view.

This invention relates to a design for the ornamentation of a corset; and, it consists in the arrangement of stays, as shown in the accompanying illustration.

On the rear section, A, is a vertical series of parallel cords, B. The hip-section has a vertical central band, C, with the representation of diagonal stays D, running from the said central band downward and rearward, and a corresponding series, E, running from said band downward and forward, both starting from about the waist-line, with the representation of a series of vertical stays, E, each side 25 the said central band above the series E D.

The rear breast-section represents a vertical series, G, of cords. The central breast-section represents a series, H, of vertical cords. On each of the breast-gores is the representation of a transverse band, I, composed of a series 30 of cords, all as shown in the accompanying illustration.

I claim—

The herein-described design for a corset, consisting of the representation of vertical cords 35 B on the rear section, the central vertical band, C, on the hip-section, the diagonal series of stays D E running from said band respectively downward and rearward and downward and forward, with the vertical series of stays F F 40 above said series D E, the vertical series of cords G on the rear breast-section, the vertical series of cords H on the central breast-section, and the transverse series I on the breast-gores, as shown in the accompanying illustration.

SEYMOUR H. ROSENBERG.
